CLAIM

The ornamental design for a charger, as shown and described.

DESCRIPTION

FIG. 1 is a front elevational view of an embodiment of a charger;

FIG. 2 is a rear elevational view of the embodiment of the charger;

FIG. 3 is a top plan view of the embodiment of the charger;

FIG. 4 is a bottom plan view of the embodiment of the charger;

FIG. 5 is a left side elevational view of the embodiment of the charger;

FIG. 6 is a right side elevational view of the embodiment of the charger;

FIG. 7 is a first perspective view of the embodiment of the charger;

FIG. 8 is a second perspective view of the embodiment of the charger;

FIG. 9 is a first reference view of the embodiment of the charger; and,

FIG. 10 is a second reference view of the embodiment of the charger.

The broken lines shown represent unclaimed subject matter and form no part of the claimed design.
